UNITED STATES PATENT OFFICE.

EDWARD M. SQUAREY AND FREDERICK KOCH, OF SOUTH ORANGE, AND ALWYN E. BORTON, OF EAST ORANGE, NEW JERSEY, ASSIGNEES TO U. S. TOOL COMPANY, INC., A CORPORATION OF NEW JERSEY.

CONDENSER PLATE SYSTEM.

Application filed April 28, 1924. Serial No. 709,395.

To all whom it may concern:

Be it known that we, EDWARD M. SQUAREY, a citizen of the Commonwealth of Newfoundland and resident of South Orange, FRED-
5 ERICK KOCH and ALWYN E. BORTON, citi-
zens of the United States, and residents,
respectively, of South Orange and East
Orange, county of Essex, and State of New
Jersey, have invented a new and useful Im-
10 provement in Condenser Plate Systems, of
which the following is a specification.

In the use of the variable condenser of
the type to which our invention relates, un-
expected and oftentimes unaccounted for
15 capacity losses have developed. These we
believe are due to the imperfect or incom-
plete contacts between the several plates of
the stator or of the rotor, whereby imper-
fect metallic connection exists. To overcome
20 this difficulty, we have designed a form of
plate system wherein the several plates of
the system are integrally connected at con-
venient points, so as to form a continuous
strip of sheet metal folded back and forth
25 from one end of the system to the other. It
is, therefore the object of our invention to
provide a plate system for variable con-
densers wherein capacity losses due to imper-
fect or incomplete metallic connection be-
30 tween the several plates are obviated, and
maximum capacities for a given number of
plates obtained.

In carrying out our invention, we make
use of the structures and methods of con-
35 struction as set forth in the following speci-
fication, taken in connection with the accom-
panying drawing, wherein—

Fig. 1 is a plan of a condenser frame with
one form of our improved plate system
40 mounted therein.

Fig. 2 is a plan of a set of stator plates
of a slightly different form.

Fig. 3 is a plan of a strip of sheet metal
45 with the stator plates laid out thereon, show-
ing the form of connection as shown in
Fig. 1.

Fig. 4 is a similar plan, but with the plates
laid out to form the system as shown in
Fig. 2.

50 Similar reference numerals refer to like
parts throughout the specification and draw-
ing.

In Fig. 1, we have shown a form of con-

denser frame, made up of the end plates 1,
2, connected by the three bolts 3, 4, 5, with 55
the stator plate system 6 mounted thereon
in the usual or any preferred manner. As
shown, the plates are spaced apart by spac-
ing washers 6, with the elongated washers 7,
8, spacing the outer stator plates from the 60
end plates 1, 2.

The individual plates 9, as shown in Fig.
3, are substantially semicircular in form,
with a notch 10 formed in the arcuate edge,
and the two notches 11, 11 upon the dia-
metrical edge, which take over the three
frame bolts 3, 4, 5. From an inspection of
Fig. 3, it will be seen that pairs of the plates
form a complete circle, with a diametrical
strip 12 cut from the center with the notches 70
11, 11 cut out at the same time. A central
circular notch 13 is also cut out to provide
for the rotor shaft (not shown). The pair
of plates 9 are connected at the circumfer-
ence by the two tangs 14, 14, and each of 75
these plates is connected to the next plates 9',
9' by the tangs 15, 15, and so on throughout
the entire strip. The strip of plates so con-
nected is then folded across the tangs 14, 14,
and 15, 15, back and forth to form the stator 80
plate system, as shown at 6 in Fig. 1, so as
to make a continuous metallic connection. It
is then assembled in the condenser frame in
the usual manner, with the spacing washers
6' inserted and maintaining the individual 85
plates in rigid parallelism.

It has not been deemed necessary to show
the rotor in connection with the stator mech-
anism, since the general construction of the
condenser is well known and understood. 90

We are able to accomplish the same re-
sults as above described by the structure
illustrated in Figs. 2 and 4. In this case
the blanking lay out shown in Fig. 4 makes
use of the individual plates 16, 16, 17, 17, of 95
substantially the same form and shape as
above described. The semicircular plates
have their straight edges ranged parallel
with the edges of the metal strip 18, and
staggered as shown to economize material.
The connecting tangs 19, 20, are immediately
adjacent the straight edges of the plates, and
are of about double the width of those
shown in Fig. 3. When folded on the dotted
lines, the plate system appears in edge view
100 as shown in Fig. 2, and is assembled in the
105

condenser frame in the same manner as above described in connection with the form shown in Fig. 1.

In stamping or punching the plate system from the strip of sheet metal in either of the forms shown, it is understood that the strip will be of a length to include an entire set of plates for a single condenser; that is to say, if it is to be what is known as an 11-plate condenser, the stator will have six plates, connected as shown; likewise, a 42-plate condenser will have twenty-two plates in the stator.

The location of the connecting tangs between the adjacent plates at their circumferences, as shown in each of the forms leaves the straight sides of the plates free for the proper interleaving of the rotor plates between them in the usual way, and at the same time makes the stator plate system of continuous metal from end to end, thereby obviating the capacity losses which are present when the plates are separate, and connected up by the contact of metal to metal.

We have confined our description and drawing to plates of substantially semi-circular shape; but we wish it understood that the improvement is applicable to plates of different shape or contour, and would be embodied in any shape of plate so long as the individual plates are integrally connected together so as to form a substantially continuous strip of metal; and we intend that the appended claims shall be so construed.

35 We claim:—

1. A stator plate system for variable condensers comprising a plurality of plates stamped from a piece of sheet metal arranged in alignment, having tangs integrally connecting a plate to one edge of the adjacent plate and integral tangs on the other edge of the second mentioned plate integrally connected to an edge of a succeeding plate.

40 2. A stator plate system for variable condensers comprising a plurality of plates stamped from a piece of sheet metal arranged in alignment, having tangs integrally connecting a plate to one edge of the adjacent plate and integral tangs on the other edge of the second mentioned plate integrally connected to an edge of a succeeding plate, whereby when said plates are folded in parallel relation with and spaced apart from each other an integral plate system is formed.

45 3. A stator plate system for variable con-

densers comprising a plurality of plates stamped from a piece of sheet metal arranged in alignment, having at least one tang integrally connecting a plate to one edge of the adjacent plate and at least one integral tang on the other edge of the second mentioned plate integrally connected to an edge of a succeeding plate.

50 4. A stator plate system for variable condensers comprising a plurality of plates stamped from a piece of sheet metal arranged in alignment, having at least one tang integrally connecting a plate to one edge of the adjacent plate and at least one integral tang on the other edge of the second mentioned plate integrally connected to an edge of a succeeding plate, whereby when said plates are folded in parallel relation with and spaced apart from each other an integral plate system is formed.

55 5. A stator plate system for variable condensers comprising a plurality of plates stamped from a piece of sheet metal arranged in alignment, having tangs integrally connecting a plate to one edge of the adjacent plate and integral tangs on the other edge of the second mentioned plate integrally connected to an edge of a succeeding plate and each plate having a notch on an edge thereof to accommodate a spacing bolt when the plates are folded in parallel relation with and spaced apart from each other.

60 6. A stator plate system for variable condensers comprising a plurality of plates stamped from a piece of sheet metal arranged in alignment, having at least one tang integrally connecting a plate to one edge of the adjacent plate and at least one integral tang on the other edge of the second mentioned plate integrally connected to an edge of a succeeding plate and each plate having a notch on an edge thereof to accommodate a spacing bolt when the plates are folded in parallel relation with and spaced apart from each other.

65 7. A condenser blank comprising a plurality of pairs of plate sections, a connecting section uniting the members of a pair of plate sections, and a connecting section uniting the pairs of plate sections, one of said connecting sections being located at the side edges of the plates, and the other of said connecting sections being located substantially at the center of the plates.
